[57] ABSTRACT

A three frame assembly for an advancing roof support, each frame having a pit prop and a roof engaging cap. A shield in the form of suspended telescoping pipes is common to the three frames and is secured to the two outer frames for movement with the same. The shield prevents packing material from entering between the frames and is contoured for this purpose. The center frame may advance and subsequently the two end frames together with the shield advances. The roof engaging cap for each frame inclines downwardly at an angle generally parallel to the angle of rest of the packing material.

HYDRAULIC SUPPORT SYSTEMS FOR MINE WORKINGS

CROSS REFERENCE TO RELATED APPLICATION

This application constitutes a division of application, Ser. No. 4,930, filed Jan. 20, 1970, and entitled Hydraulic Support Systems for Mine Workings, now U.S. Pat. No. 3,618,325.

BACKGROUND OF THE INVENTION

Shields for protecting the advancing roof prop assemblies for mine use are concerned in this instance. Such shields particularly bent to U-shaped replace wire netting, papers or wires formerly utilized frequently as packing shields, because the durability of such shields is not good, and with the great advances in the art, which make possible the advancing hydraulic mine roof support, these shields had to be replaced too frequently. The use of the shields frequently formed from sheet metal must, however, on the one hand, take place so that the support assembly can advance, and on the other hand, the shielding of dirt or the like during advance cannot permit the entrance of lumpy material into the retaining space for the props.

A two frame assembly is already known which utilizes two sheet metal parts as shielding members which are suitably joined or articulated with one another. Such shielding members, on account of the mobility afforded by the frame joints or articulations, are easily subjected to damage by material containing coarse pieces or lumps. The known shielding members made of U-shaped sheet metal up to now do not make possible the reliable shielding of the space between two or more frames when they are combined into one unit. Therefore, material gets into this space and easily blocks the advancing movement of the mine roof supports. Besides, the danger exists that the advancing devices, particularly the hydraulic props, which are ordinarily arranged between the frames, are damaged.

SUMMARY OF THE INVENTION

The invention provides a three frame assembly for an advancing mine roof support, which is provided with a material shielding means for shielding in all phases of the advance, the entire bottom and also the intermediary spaces between the frames against the penetration of packing material. In accordance with the basic idea of the invention, this is achieved by the use of a shield fixed only to the two outer frames but covering all three frames. The shield is formed by a curtain of closely spaced telescoping pipes, the ends of which are secured to the outer frame assemblies respectively.

Upon advance, then first the center frame is pushed forward, which takes place protected from the packing insulation, which remains at the breakage edge, and is held in place by the two outer frames. When the outer frames are brought up or advanced, the shield moves up to the middle frame which has already been pushed along on the packing side of the prop support. Therefore, the shield can prevent neither the advance of the outer frames, nor the advance of the inner frame. The packing material on the surface is present only between two consecutively disposed three frame assemblies and not between the frames of an assembly. In view thereof, no packing material can penetrate to the base plate means of the three frame assembly.

According to the invention, the rear ends of the mine roof engaging caps incline downwardly, so that in the driving position of the frame assembly a plane touching the cap ends, whose incidence is parallel generally to the angle of inclination of the packing material, encounters a rear angular portion of the U-shaped shield. Thus, it is possible to keep the height of the U-shaped shield relatively low, and not only save material and weight, but also restrain the packing material.

10

BRIEF DESCRIPTION OF THE DRAWINGS

FIG. 1 is a side elevation of a shield for a three frame assembly for an advancing mine roof;

FIG. 2 is a side elevation; and

FIG. 3 is a horizontal section on the line 3—3 of FIG.

1.

DESCRIPTION OF THE PREFERRED EMBODIMENT

The three frame assembly illustrated in the drawings consists of frames A, B, C with hydraulic props or roof supports on the packing side (only prop A1 being shown), base-rails A2, B2, C2 and roof supporting caps A3, B3, C3.

In the embodiment by way of example according to FIGS. 1 to 3, the upper supporting caps on the packing side are constructed in predetermined manner, which is to be explained more in detail in the example of the cap 30 A3. The end 5 of this cap facing the packing is inclined downwardly so that at 6 the upper peak of the angle results, which includes the downwardly inclined end portion 5 joined to a forwardly extending front part 7. At the peak of the angle there is formed a breakage edge D extending upwardly and illustrated in dotted lines. At the outer end of the part 5 of the cap occurs the packing slope.

On the packing side there is arranged a curtain formed by a row of closely spaced telescoping rods 30 providing a flat shield covering the three frames A, B, and C. A transversely extending beam 13 on the packing side is secured respectively to the props A' and C'. The frames A and C are advanced simultaneously by suitable hydraulic rams (not shown) after the middle frame B has advanced.

The telescoping rods 30 consist of upper pipes 33 which are guided telescopically in lower pipes 31. The bottom ends of the lower pipes 31 are secured to a bracket 36 which is secured only to the base rails A₂ and C₂ of the frames A and C respectively. The upper ends of the rods 33 are secured to a horizontal guide rod 32 which is connected only to the roof supporting caps A₃ and C₃ as indicated at 34 and 35.

What we claim is:

1. In an advancing mine roof support, a three frame assembly for advancing mine roof support, each frame assembly having a base rail, a hydraulic roof support and a roof supporting cap, a shield extending across the rear of said frames and consisting of a row of closely spaced vertically disposed telescoping rods, means providing a connection between the upper rods and the caps of said end frame assemblies, means providing a connection between the lower rods and the base rails of said end frame assemblies,

bracket means on each of the outer frame assemblies, and beams extending transversely of said shield and secured at opposite ends to said bracket means, thereby enabling the outermost frame assemblies along with said shield to be advanced while the intermediate assembly is under load, and the intermediate assembly is advanced when the outermost frame assemblies are under load.

2. In an advancing mine roof support as claimed in claim 1, in which said connection means between the

upper rods and the end frame assembly caps comprises a guide rod connected respectively to the caps of the outer end frames, and a connection between the upper end of each upper rod and said guide rod.

5 3. In an advancing mine roof support as claimed in claim 1, in which said connection between the lower rods and the base rails comprises a bracket supporting the lower ends of the lower rods of the screen, and a connection between said bracket and the outer frame assemblies.
